UNITED STATES PATENT OFFICE.

CHARLES W. DAVIS, OF EDGEWORTH, PENNSYLVANIA, ASSIGNOR TO STANDARD UNDERGROUND CABLE COMPANY, OF PITTSBURGH, PENNSYLVANIA, A CORPORATION OF PENNSYLVANIA.

ELECTRIC FUSE.

1,152,148.

Specification of Letters Patent. Patented Aug. 31, 1915.

Application filed April 22, 1913. Serial No. 762,887.

To all whom it may concern:

Be it known that I, CHARLES W. DAVIS, residing at Edgeworth, in the county of Allegheny and State of Pennsylvania, a citizen of the United States, have invented or discovered a certain new and useful Improvement in Electric Fuses, of which improvement the following is a specification.

My invention relates to electric cut outs or fuses for high voltage currents, and has particularly to do with fuses wherein a conducting element extends between two terminals and consists of a relatively low fusible portion and adjoining high fusible portions.

The objects of my invention are, first, to provide a simple and effective means for widening the gap between the high fusion portion of such conductors upon the blowing of the low fusion portion, and for simultaneously breaking the circuit at a second point; and secondly, to provide simple and effective means for relieving the tensile strain upon the low fusion portion of the conductor when a spring or other yielding means is employed for effecting a widening of the gap between the high fusion portions thereof.

In the accompanying drawing, which forms part of my specification, I have illustrated several embodiments of my invention.

Figure 1 of the drawing is a vertical sectional view of a junction box showing two entering cables and a removable fuse structure, the casing inclosing the fusible conductor being shown in longitudinal section; Fig. 2 is a longitudinal sectional view of another form of fuse illustrating a different embodiment of my invention; and Fig. 3 is a detached detail of construction.

In the several figures like numerals are used to designate like parts.

The general structural features of the complete fuse and its installation shown in Fig. 1 are similar to those illustrated and claimed in my application, Serial No. 762,886, filed of even date herewith. It will, however, be readily apparent that my invention may be employed in various other forms and installations than that particularly shown and described herein.

Referring first, and briefly, to the general construction and installation in which my invention is illustrated and subsequently to the features of my invention, the junction

box 1 is provided with two entering cables 2, to each of which is secured a terminal structure 3, comprising in part a spring-clip contact 4 and a guide post 5. The removable fuse structure comprises a frame 6 of insulating material; conducting brackets 7 and 7^a, secured to said frame, and having knife-blade contacts 30 at their lower ends; and, extending between said contacts, the fusible conductor, casing, etc., explained more fully hereinafter. As will readily be seen the frame 6 is provided with a handle 8 and with guide-ways 9, adapted to engage the guide posts 5, such an arrangement being particularly desirable when an arc-dampening liquid fills the junction box, as in the present instance.

In Fig. 1 of the drawings, the casing 10, which is cylindrical and formed of a suitable insulating material, is secured to the brackets 7 and 7^a, and has its open ends closed by means of closures 11 and 12, the latter of which fits loosely. The casing is provided with a partition 13; and the conductor comprising high fusion portions 14, 15 and a low fusion portion 16, extends through the casing, the high fusion portions 14 and 15 being secured to the closures 11 and 12, respectively. The outer ends of the conductor 14 is electrically connected by means of a flexible wire 17 to a binding screw 31 of the bracket 7; while the electrical connection between the conductor 15 and the bracket 7^a is such that, when the closure is removed after the blowing of the fuse portion 14, a second opening of the circuit will be effected. In my preferred construction to such an end, the closure 12 is provided with a contact cap 32, to which the conductor 15 is electrically secured, by a screw 33, and which in turn is electrically connected to the bracket 7^a by means of spring contact arms 34. It will be readily seen of this construction that the blowing of the low fusion portion 16 of the conductor will be effective to remove the closure 12 from the casing 10 and to carry with it the high fusion portion 15, and also that the circuit will be broken between the closure 12 and the bracket 7^a. The construction, illustrated in Fig. 2 of the drawings, is, as far as this feature of my invention is concerned, the same as that illustrated in Fig. 1, and just described. Means are also provided for dampening or break-

ing the arc, which usually forms between the free ends of the high fusion portions of the conductor after the low fusion portion has been destroyed. To such an end I divide 5 the fuse casing into two chambers, an explosion chamber and a retracting chamber, and I provide means for withdrawing one of the high fusion conductors through a small opening in the chamber-dividing partition 10 and into the retracting chamber, thereby quickly drawing out and quenching the arc which may have been established.

In Fig. 1 the partition 13, formed preferably of insulating material and having a 15 small opening 18 through the center of it, divides the casing 10 into an explosion chamber 19 and a retracting chamber 20. The means for drawing the conductor 14 through the opening 18 and into the retracting chamber 20 consist, in this instance, of a coil spring 21 formed of the conductor 14 itself, which, in order to have good conducting qualities and at the same time be sufficiently yielding, may be made of copper coated steel wire. 25 It will be understood that, when such a conductor is thus coiled into a spring, the electromagnetic action of the current flowing through the conductor will materially increase its tension. In Fig. 2 the spring 21^b 30 is independent of the conductor 14^b, and, being preferably formed of high resistance material, will receive little, if any, of the current carried by such conductor, and hence will exert less stress due to electromagnetic 35 action.

Another feature of my invention has to do with means for relieving the low fusion portions of fuse conductors from strains normally placed upon them by yielding elements such as the springs just described. In 40 fuses for high voltage and low amperage currents, the fusible portion of the connecting conductors must, particularly when surrounded by an arc-dampening liquid, be 45 very small in cross-section and hence of small physical strength. When, therefore, such fusible portion becomes heated, and its strength diminished accordingly, it is liable to rupture under the strain of a continuously 50 acting spring or like element before its rated current-carrying capacity has been reached. In order to eliminate this difficulty I provide means for relieving the tension upon the low fusion portion of the conductor, but in no way interfering with the 55 action of the tension producing means to remove or withdraw the high fusion portion of the conductor after such low fusion portion has melted. The simplest means, which 60 I have illustrated to this end, are shown in Fig. 2, wherein the ends of the high fusion portion 14^b and 15^b are mechanically connected by means of a strip 35, which will carry little if any of the current flowing 65 through the fuse strip, but which will be

ruptured by the blowing of the low fusion portion 16^b, which, it will be seen, will not be subjected to any tension when carrying a current. The strip 35 may be made of non-conducting material such as glass fiber, 70 or quartz fiber, or may be made of a low conducting metal such as a fine steel wire, all of which materials will relieve the low fusion portion 16^b of the tension placed upon the other parts of the conductors, but which 75 will readily be fused or broken upon the fusion of said portion 16^b. Furthermore, it is characteristic of the materials mentioned that they are non-combustible, and hence upon their fusion do not add materially to 80 the volume of gases formed in the fuse casing by the explosion of the fuse. In Fig. 3 I have illustrated a similar means for relieving the tension from the low fusion portion of the conductor, wherein fusible or dis- 85 ruptable tension strips 35^a and 35^b are secured to the opposite ends of non-conducting arms 36 and 36^a, respectively, which arms are in turn secured to the high fusion portions 15^a and 14^a. The strips, or cords 90 35^a and 35^b are looped through each other, and each is connected to the opposite ends of a single arm, so that the high fusion portions will be free to move when either of 95 said strips is disrupted.

In the construction shown in Fig. 1 a disruptive or fusible cord 25, indirectly relieves the tension upon the low fusion portion 16, such strip in this particular arrangement extending transversely of and adjacent to said portion 16, and being connected at one end to the casing 10 and at the other end to one arm of a pivoted lever 24. The opposite arm of said lever engages the arm 23 of an insulated bell-crank lever 22, 23, 100 105 the arm 22 thereof engaging a loop 39 formed in the high fusion portion 14 at the end of the spring 21. The arrangement is such that the cord 25 holds the lever 24 and bell-crank lever 22, 23 in the tension-relieving position shown in the drawing while normal currents are flowing through the fusible portion 16, but when the said portion 16 blows (by reason of an abnormal current) 110 said cord 25 is disrupted or fused and releases the lever 24, and hence the spring 21. In order to accelerate or make more certain the disruption or fusion of the tension cord 25, said cord may extend through a stopper or plug 26 adapted to close an opening 27 in 115 the casing 10, the arrangement being such that the explosive force of the fusion portion 16 will act against the stopper 26 and expel it from the casing opening 27.

The operation of the fuse illustrated in 120 Fig. 1 is as follows, assuming that the parts thereof are arranged in their normal operative position, as shown therein: When the current carried from one cable conductor to the other through the fuse conductor 14, 16 125 130

and 15, exceeds a predetermined abnormal strength, the low-fusible portion 16 blows, the explosive force being effective to remove the closure 12 from the casing, and the arc 5 momentarily formed being effective to rupture the wire 25. The closure 12 will carry with it the conductor portion 15, thereby widening the gap between the end of said conductor portion and the adjacent end of 10 the portion 14, and will also effect a second breaking of the circuit between such closure and the bracket 7^a. Upon the rupture of the wire 25, either through its fusion or through the tension added to it by the explosive force 15 acting upon the plug 26, the right hand end of the lever 24 will rise and release the bell-crank lever 22, 23 so that the spring 21 will be effective to draw the free end of the conductor portion 14 through the partition 13 20 and 14 into retracting chamber 20, thereby dampening the arc and also widening the gap between the free conductor ends.

I claim as my invention:

1. In an electrical installation, the combination of a pair of electrical conductors, and an electric fuse closing a circuit between said conductors, said fuse comprising a casing having an opening therein, a removable closure for said opening, a contactor electrically secured to one of said conductors, a second contactor secured to said closure and adapted to contact with the first named contactor when said closure is in the casing opening, a fuse strip comprising a low fusion 25 portion and adjoining high fusion portions, one of said high fusion portions being electrically secured to the contactor attached to said closure, said closure being removable from said casing on and by the blowing of said low fusion portion and by such movement simultaneously effective to widen the gap between the high fusion portions of said fuse strip and to release said contactors 40 from engagement with each other.
2. In an electric fuse, the combination of a casing, a fuse strip within said casing comprising a low fusion portion and adjoining high fusion portions, yielding means secured to a high fusion portion and effective 45 to exert a pull thereon upon the blowing of the low fusion portion, and means including a fusible noncombustible cord for relieving said low fusion portion of the pull of said yielding means, said cord being fusible upon 50 and by the blowing of said low fusion portion.

3. In an electric fuse, the combination of a casing, a fuse strip within said casing comprising a low fusion portion and adjoining high fusion portions, yielding means 60 secured to a high fusion portion and effective to exert a pull thereon upon the blowing of the low fusion portion, and means including a fusible wire for relieving said low fusion portion of the pull of said yielding means, said wire being fusible upon and by the blowing of said low fusion portion.

4. In an electric fuse, the combination with a conductor comprising high and low fusion portions, of a spring secured to said 70 high fusion portion and adapted upon the blowing of said low fusion portion to move said high fusion portion away from the zone of fusion, a pivoted finger effective in one position to withstand the strain of said 75 spring and means for holding said finger in said position, said holding means being rendered ineffective for such purpose upon the blowing of said low fusion portion.

5. In an electric fuse, the combination 80 with a casing, and a conductor comprising high and low fusion portions; of a spring exerting its tension on said conductor and adapted upon the blowing of said low-fusion portion to move a free end of said 85 high fusion portion away from the zone of fusion, a finger pivotally borne by said casing and adapted to engage said spring and withstand the tension thereof, and means for holding said finger in spring-engaging 90 position, said finger-holding means being rendered ineffective upon the blowing of the low fusion portion of said conductor.

6. In an electric fuse, the combination of 95 a casing, a partition dividing said casing into explosion and retracting chambers, a conductor extending through said casing and partition and provided within said explosion chamber with a low fusion portion, said conductor forming a coiled tension 100 spring within said retracting chamber, a finger pivoted to said casing and engaging said spring, and means including a portion 105 destructible upon the blowing of the fuse for holding said finger in spring-engaging position.

In testimony whereof I have hereunto set my hand.

CHARLES W. DAVIS.
